WINDOW BLIND

Charles P. Kegley, Pulaski, Va.

Application December 11, 1945, Serial No. 634,188

9 Claims. (Cl. 20—62)

1

This invention relates to the class of window accessories and pertains particularly to blinds and more especially to the type known as Venetian blinds.

A principal object of the present invention is to provide a blind structure which is so designed as to be readily inserted into a window frame or opening and which is provided with slats mounted in a novel manner to be readily oscillated to opened or closed position.

Another object of the present invention is to provide a slat blind which is initially set-up as a complete unit ready for installation in a window frame and which has the slats set in the frame in a novel manner whereby any one may be removed and replaced without taking the frame out of the window frame and without taking any of the adjacent slats from position.

Still another object of this invention is to provide in a window blind structure of the character stated, a novel manner of mounting the individual slats for turning, such mounting being so designed that a relatively large circular bearing is provided for each end of each slat without the employment of pins or trunnions.

A further object of the present invention is to provide a blind structure having a frame in which opposite side members are provided upon their inner faces with vertically spaced bearing ribs and each of the slats is attached at each end to a bearing disc which is mounted between a pair of ribs and retained in position for turning action upon the lower one thereof.

A still further object is to provide, in a structure of the character stated, a novel slip coupling between the ends of the slats and the bearing discs, by means of which any slat may be disengaged from its bearing disc and also whereby any slat may be separated from the slip coupling after the coupling and disc are separated.

Other objects and advantages of the invention will become apparent as the description of the same proceeds and the invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in perspective of the top

2

portion and a part of the lower portion of a slat blind constructed in accordance with the present invention.

Figure 2 is a detail section taken transversely of two slats and looking toward the end bearings by which they are mounted in a side of the frame.

Figure 3 is a face view of a bearing disc.

Figure 4 is a perspective view of an end of a slat showing the coupling by which it is joined to a disc.

Figure 5 is an edge view of a disc.

Figure 6 is a perspective view of a portion of a bearing rib plate showing a preferred manner of forming the bearing rib.

Referring now more particularly to the drawing, the numeral 10 generally designates the frame of the blind. This frame may be made in any desired size to fit in and extend from the top to the bottom of a window frame or to cover a part thereof if desired, such for example as the lower half.

As shown the frame consists of the upper and lower horizontal bars 11 and 12 and the vertical side bars 13. Preferably, though not necessarily, the horizontal bars are formed of wood while the vertical bars are formed of sheet metal.

When so constructed the side bars have at their two ends the inwardly directed side ears 14, between which an end of a horizontal bar is positioned and secured. Thus there is obtained the finished rectangular frame 10, which, when made of proper dimensions, may be set in and secured to the window frame in which it is to be used.

At each longitudinal side of each vertical bar, between the ears 14, a portion of the bar 13 is turned in to provide a guide flange 15. These flanges, at the opposite sides of each vertical bar, are spaced from the body of the bar to form a channel 16, for the purpose about to be described.

The width of the channel 16 is sufficient to receive the edges of a long, flat plate 17 and the peripheral portion of a bearing disc 18.

The plate 17 has disposed transversely thereof at intervals, the bearing ribs 19. The spaces between the ribs are only slightly greater than the diameter of a disc. Also as will be readily apparent upon reference to Figures 1, 2 and 6, the ribs 19 are of a length substantially equal to the distance between the opposing edges of the guide flanges 15. Thus when the plate 17 is inserted in the guide grooves 16, this being done before one of the horizontal rails is secured in position between the vertical bars 13,

the ends of the ribs 19 will be securely held between the opposing edges of the flanges 15.

While any suitable means may be provided for forming the ribs 19, the method illustrated particularly in Figure 6 is preferred. In this method of forming a rib it will be seen that the plate 17 is provided at each edge with cut out portions or transversely extending short slots 20, the extent of the slots, which are arranged in pairs transversely of the plate, being such as to leave an intervening portion of the plate material of a width to form the desired length of bearing rib. Such intervening portion of the plate material between the slots 20 is then folded along a center line extending transversely of the plate and along lines alining with the edges of the slot 20 so that such intervening portion of material is brought into a rib form to project from the face of the plate 17 as shown in Figure 6.

The distance between the opposed bottoms of the channels 16 is substantially the same as the distance between adjacent pairs of bearing ribs 19 and these distances are substantially equal to the diameter of a disc 18. Thus it will be seen that when a disc is interposed between a pair of bearing ribs 19, with opposite sides of its periphery in the channels 16, it will be maintained against movement transversely of the vertical bar 13 and also against movement longitudinally thereof but it may rotate freely, there being, of course, an allowance made of sufficient clearance between the edge of the disc and the bearing ribs and the bottoms of the guide channels, to permit such free rotation without, at the same time, allowing such looseness as to permit rattling.

Each of the bearing discs 18 is provided with two spaced parallel slots 21 which extend across the discs on opposite sides of the center and the portion of the disc material between the slots 21 is pressed outwardly from the face of the disc to provide the relatively long loop or keeper band 22. On one side of this band 22 and spaced from and in alinement with the transverse center of the band, the disc 18 is pressed to form the outstanding keeper lug 23 which projects from the face of the disc nearest to the band 22 and from which the band 22 is spaced.

Within the frame 10 and extending transversely thereof between the vertical side bars 13 is a plurality of spaced parallel flat slats, each of which is designated 24.

The slats 24 are attached at each end to a bearing disc 18 through the medium of a coupling unit which is generally designated 25.

Each of the coupling units 25 comprises a boot 26 which is formed from a flat plate 27 of suitable metal, having portions of each side turned to provide the spaced flanges 28, the spaces between the flanges and the body of the plate providing grooves or channels 29 in which an end of a slat 24 is positioned.

At one end of the boot 26 there is provided the transversely extending shoulder 30 which is formed integral with a tongue 31, which is spaced from the adjacent end of the boot and which is of decreased width at its free edge as indicated at 32. In the structure here shown the shoulder 30 and tongue 31 are formed as an integral continuation of a portion of the metal plate 27 which provides the boot 26 but it is to be understood that, while this is the preferred manner of forming this connector, it

may be formed in any other suitable manner.

The width of the tongue 31 is such as to facilitate its snug engagement under the holding band 22, the tongue extending across the face of the disc 18 to which it is attached. The free end of the tongue is started under the band 22 and across the face of the disc adjacent to the band, from the side of the band nearest to the lug 23 and when the tongue has been forced through under the band the shoulder will ride across the lug and finally come to position against the side of the lug nearest to the band. In other words the top edge of the shoulder will engage the lug and thus hold the tongue against escape from beneath the band 22. It will be understood that the disc will have sufficient resiliency to allow the tongue to pass across the lug and under the band until the shoulder has come into the desired position and when such position is reached the lug will prevent reverse movement of the tongue unless force is applied.

It will be readily apparent that the connectors 25 may be engaged with or disengaged from the disc 18 and that, therefore, the slats 24 which have their ends inserted into the connector boots 26, can be readily removed or replaced from the blind structure without having to take down the blind or disassemble it in any manner.

Several slats of the blind are loosely coupled together by a bar 33 through the medium of the interconnected eyes 34, in the usual manner of coupling together the slats of blinds of this character. By such means all of the slats may be turned or oscillated together when it is desired to open or close the blinds.

From the foregoing it will be readily apparent that the blind of the present invention is of such design that the various parts thereof may be easily and quickly made by stamping from sheet metal of suitable weight and readily assembled and installed in position. It will also be apparent that by reason of the novel construction of the vertical side bars the maximum width of a window opening may be utilized for the admission of light and air. Furthermore, it will be seen that by the provision of the novel bearing discs at the ends of the slats, mounted in the opposing channels of the vertical side bars, between the vertically spaced bearing ribs, the structure may be easily set up without the necessity of forming bearing openings or apertures for pivot trunnions such as are commonly employed in other blind structures of a similar character.

55 I claim:

1. A blind structure designed to be installed within a window frame, comprising a frame unit having vertical side bars, a plurality of blind slats disposed transversely between said vertical bars, 60 a disc member mounted upon each end of each slat and disposed in close proximity to the inner side face of a vertical bar, means disposed inwardly with respect to said inner side faces of the vertical bars forming bearings between which the discs are disposed for rotation and means overlying said faces and maintaining the discs between the bearings.

2. A blind structure of the character stated in claim 1, with interconnecting elements between 70 the ends of the slats and the discs, facilitating the disconnection of the slats from the discs without removing the discs from position upon the supporting bars.

3. A blind structure of the character stated, 75 comprising a pair of spaced, parallel bar mem-

bers having flat inner faces, the bar members being designed to be positioned vertically within a window frame, a plurality of blind slats disposed in spaced parallel relation between said bars and having their ends in close proximity to the bars, a flat, circular bearing element at each end of each slat, means coupling each bearing element with the adjacent slat to position the radial center of the bearing element at the longitudinal center of the slat, said bearing elements being disposed in front of and in parallel relation with and in close proximity to the inner faces of the adjacent vertical bars, elements disposed in spaced relation with one another and supported by said bars providing bearing surfaces upon which the circular bearing elements are rotatably supported, and means retaining the bearing members in position between said elements.

4. A blind structure of the character stated in claim 3, in which the said elements disposed in spaced relation with one another and supported by the vertical bars comprise a series of vertically spaced, transversely extending ribs between adjacent pairs of which the circular members are maintained, a lower one of each of the ribs having a circular member rotatably supported thereon.

5. A blind construction of the character stated, comprising a pair of spaced parallel bar members adapted to be disposed in vertical position within a window frame, each of said bar members having longitudinally extending spaced guide channels upon its inner face, a plurality of bearing ribs supported in vertically spaced relation and transversely of the inner surface of each bar, between the adjacent spaced channels, a disc member disposed between adjacent pairs of ribs and having opposite sides of its periphery rotatably engaged in the adjacent opposed channels, one of the ribs adjacent to each disc forming a bearing surface upon which the periphery of the disc turns, a plurality of slats disposed in spaced parallel relation between the vertical bars, and means connecting each slat at each end with a disc for rotation therewith.

6. A blind construction of the character stated, comprising spaced parallel bar members adapted to be disposed in vertical position within a window frame, each bar member having longitudinal spaced guide channels, disc members disposed between and having their peripheries engaged in the guide channels of each bar member, means supporting the disc members for rotation, a plurality of slats disposed in spaced parallel relation between the vertical bars, and a separable coupling connecting each slat at each end with a disc for rotation with the disc and for ready detachment from and attachment to the disc.

7. A blind construction of the character stated in claim 6, wherein the said separable coupling for detachably connecting each end of the slat with a disc comprises a tongue carried at

the end of a slat and extending transversely across the same, a loop carried by the disc for receiving the tongue, and means for releasably holding the tongue in the loop, said loop being set inwardly from the plane of the inner face of the disc to facilitate the withdrawal of the tongue from the loop.

8. A blind structure of the character stated in claim 6, wherein the said means for connecting the ends of the slats with the disc comprises a boot member in which the end of the slat is engaged, a tongue formed integral with the boot member and extending transversely of the adjacent end of the slat, means forming a shoulder at one end of the tongue, a keeper loop carried by and extending across the center of each disc beneath which the said tongue is frictionally engaged, and means carried by each disc adjacent to the loop for engagement over the adjacent shoulder when the tongue is frictionally engaged in the loop to prevent accidental displacement of the tongue from beneath the loop.

9. A blind structure of the character stated, comprising a pair of spaced, parallel bar members having flat inner faces, the bar members being designed to be positioned vertically within a window frame, a plurality of blind slats disposed in spaced parallel relation between said bars and having their ends in close proximity to the bars, a flat, circular bearing element at each end of each slat, means coupling each bearing element with the adjacent slat to position the radial center of the bearing element at the longitudinal center of the slat, said bearing elements being disposed in front of and in parallel relation with and in close proximity to the inner faces of the adjacent vertical bars, elements disposed in spaced relation with one another and supported by said bars providing bearing surfaces upon which the circular bearing elements are rotatably supported, the last named means being provided at opposite longitudinal edges of said vertical bars, and the coupling means between the ends of the slats and the circular members comprise interlocking parts by means of which the slats may be disconnected from the circular members while such members are maintained in position with respect to the supporting bars.
